SHOE

Bernard W. Price, San Francisco, Calif.

Application October 15, 1949, Serial No. 5,501

Term of patent 7 years

(Cl. D7—7)

To all whom it may concern:

Be it known that I, Bernard W. Price, a citizen of the United States and a resident of the city and county of San Francisco, State of California, have invented a new, original, and ornamental Design for a Shoe, of which the following is a specification, reference being had to the accompanying drawing, forming a part thereof.

Figure 1 is a perspective view of a shoe, showing my new design; and

Figure 2 is a side view thereof.

The characteristic feature of my design resides in the provisions of a heavy welting running along the sides of the shoe near the opening, said welting being provided with V-shaped cuts transversely of the same, all as illustrated.

I claim:

The ornamental design for a shoe, as shown and described.

BERNARD W. PRICE.
